HAIR CURLING DEVICE

Mary Urs, Youngstown, Ohio

Application May 7, 1934, Serial No. 724,432

6 Claims. (Cl. 132—33)

The invention has to do particularly with apparatus to aid in the production of what is referred to as a permanent wave in the hair.

The usual apparatus now employed includes a rod upon which the hair is curled or wrapped in preparation for treatment. Ordinarily a small strand of hair is tied by string more or less firmly to one end of the curling rod and then wrapped around the rod a suitable number of times and then the end tied to the rod. This method of operating has numerous disadvantages well known in the art. The present invention contemplates the production of a clip device which will clasp and more or less tightly hold a small strand of hair near the scalp. The usual curling rod may be attached to the clip and the hair held by the clip at one end while it is turned or coiled about the rod and finally fastened at the end thereto.

It being understood that the invention is not confined to the specific details, there is illustrated in the accompanying drawing one form the invention may take. Figure 1 is a vertical side elevation of a clip and the associated rod about which hair has been wound. Fig. 2 is a side elevation on a somewhat enlarged scale of the clip and the end of the rod. Fig. 3 is a transverse vertical section through the middle of Fig. 2. Fig. 4 is a transverse vertical section on the line 4—4 of Fig. 2. Fig. 5 is a transverse vertical section on the line 5—5 of Fig. 3.

The clip may consist of an upper member 10 and a lower member 11 pivoted together on a pivot shown as a rivet 12. A leaf spring 13 at one side of the pivot 12 tends to hold closed the jaws of the members 10 and 11. The leaf spring 13 rests within the handle portion 14 of the member 10 and the handle portion 15 of the member 11 and tends to hold the handles separated. The end of the member 10 on the other side of the pivot 12 from the handle 14 may consist of a transversely arc shaped portion indicated in Fig. 5 at 16. The arc shaped portion 16 normally engages a similarly formed circular nose portion 17 of the member 11. Inwardly from the nose there is provided in the member 10 a cavity 18 which may be semi-elliptical in form and at a corresponding position in the member 11 is a similarly oppositely disposed semi-elliptical opening 19. The arrangement is such that by forcing together the hand pieces 14 and 15 against the leaf spring 13 the portions 16 and 17 are separated to a small extent allowing a limited size strand of hair to be forced into the cavity formed by the semi-elliptical openings 18 and 19 and when the han-

dles 14 and 15 are relaxed the strand of hair will be more or less rigidly clasped and held in the cavity formed by 18 and 19. In order to aid in firmly fixing the strand of hair and to hold it from slipping there may be provided a longitudinal ridge 20 in the semi-elliptical opening 19. This arrangement insures a relatively tight hold on the hair keeping the clip in place, and because the outlines of the opening are curvilinear the possibility of abrupt tearing, damaging and breaking the hair is reduced to a minimum. Likewise the curved surfaces 16 and 17 which may engage some hairs which do not become amalgamated with the strand in the opening between 18 and 19 are so formed as to avoid sharp bends in the hair thus tending to eliminate damage or breakage of the hair.

The front end of the member 11 is illustrated as provided with a filling block 21 in which is made the ridge 20. This is not essential as the member may be made all in one piece. It will be noted that the front end of the member 11 and filling block 21 are carefully curved so as to readily pass through the hair without catching it so as to avoid pulling, tearing or breaking the hair. Likewise the front end of the member 10 is curved or smoothed so as to easily and comfortably pass through the hair.

The curling rods about which the hair is commonly coiled for the curling operation consist of an inner and an outer member so arranged that they may be manipulated to allow relative rotation. Such devices have the inner central member firmly screwed into a tip piece which engages the outer member. Such rods may be used in the ordinary way with the clip. One phase of the present invention contemplates providing on the hair-holding clip a seat for such a curling rod. The particular location of the seat on the clip is not essential but is illustrated at 22 on the member 10 about over the pivot 12. The seat 22 comprises a central threaded opening 23 surrounded by an annular cavity 24. The usual tip supplied with the well known curling rods in general use may be removed and the outer or sleeve member 25 of the curling rod may be fitted into the annular cavity 24. The inner or central shaft 26 of the curling rod is provided with external threads and may then be screwed into the central cavity 23. In this position the hair held by the clip may be wound or curled upon the curling rod and the coil of hair may be tightened thereon in the usual manner by manipulating the head 27 of the curling rod to allow relative rotation of the sleeve 25 about the central pivot 26.

- The pivot 12 which holds together the members 10 and 11 may be provided at one side with an enlarged head 28 forming a groove 29 to which may be attached means for fastening the hair 5 such as a wire, thread or string 30. The wire, thread or string 30 may be placed in the strand of hair and coiled with it about the curling rod 25 and may form means for fastening the strand of hair and especially its end to the curling rod.
- 10 If wire of suitable material is employed it may be sufficient to merely wrap it a few times around the rod and hair or it may be tied which may be especially necessary when thread or string is employed. The arrangement of the groove 29 15 on the head of the rivet 12 being without the clip is so arranged that replacement of the wire when necessary is simple and at the same time and in the same way thread or string may be substituted for the wire.
- 20 It will be seen that there is provided simple, convenient apparatus which may be quickly and readily assembled and disassembled and which easily lends itself to thorough and successful cleaning while at the same time providing an 25 easily applied and adjusted means for surely holding the hair in place in the manner desired for the subsequent operation of making the curl permanent.

I claim as my invention:

- 30 1. A clip having a curvilinear aperture for clasping a strand of hair, a seat thereon, a curling rod in the seat, and a wire fastened to the clip and adapted to fasten hair to the rod.
2. A clip comprising an upper and a lower member, a pivot holding them together at near their 35 middles, handle members for each member, a substantially circular nose for the lower member, a longitudinal ridge in a transverse aperture in the nose, a curved nose for the upper member adapted to lie against the circular nose of the lower member and provided with a transverse aperture cooperating with the transverse aperture in the nose of the lower member to form a seat for a strand of hair, means to normally hold 40 the noses of the upper and lower members together but allowing them to separate a limited amount, a threaded seat on the upper member surrounded by an annular cavity, a curling rod having a central core engaging the threaded seat and a 45 surrounding sleeve in the annular cavity, and an extension on the pivot for receiving means for fastening hair in place on the rod.
- 50 3. A clip comprising an upper and a lower mem-

ber, a pivot holding them together, a substantially circular nose for the lower member having a transverse aperture therein, a curved nose for the upper member adapted to lie against the circular nose of the lower member and provided with a transverse aperture cooperating with the transverse aperture in the nose of the lower member to form a seat for a strand of hair, means to normally hold the noses of the upper and lower members together but allowing them to separate a limited amount, a seat on the upper member, and a curling rod engaging the seat.

4. A clip comprising an upper and a lower member, a pivot holding them together, a substantially circular nose for the lower member, a longitudinal ridge in a transverse semi-elliptical aperture in the nose, a curved nose for the upper member adapted to lie against the circular nose of the lower member and provided with a transverse semi-elliptical aperture cooperating with the transverse aperture in the nose of the lower member to form a seat for a strand of hair, means to normally hold the noses of the upper and lower members together but allowing them to separate a limited amount, a threaded seat on the upper member surrounded by an annular cavity, a curling rod having a central core engaging the threaded seat and a surrounding sleeve in the annular cavity, and an extension on the pivot for receiving means for fastening hair in place on the rod.

5. A clip comprising an upper and a lower member, a pivot holding them together, a substantially circular nose for the lower member, a longitudinal ridge in a transverse aperture in the nose, a curved nose for the upper member adapted to lie against the circular nose of the lower member and provided with a transverse aperture cooperating with the transverse aperture in the nose of the lower member to form a seat for a strand of hair, means to normally hold the noses of the upper and lower members together but allowing them to separate a limited amount, and an extension on the pivot for receiving means for fastening hair in place.

6. A clip having a curvilinear aperture for clasping a strand of hair, a seat thereon comprising a threaded lug surrounded by an annular cavity, a curling rod having a central shaft engaging the lug and a sleeve in the cavity, and a wire fastened to the clip and adapted to fasten hair to the rod.
